SIGNALING MEANS FOR STORAGE TANKS

Harry F. Tapp, Longmeadow, Mass., assignor to
 Gilbert & Barker Manufacturing Company,
 West Springfield, Mass., a corporation of Mas-
 sachusetts

Application April 8, 1938, Serial No. 200,818

3 Claims. (CL 137—111)

This invention relates to an improved signaling means for use in connection with storage tanks of liquid for giving a signal during the filling of the tank and to indicate when the tank is nearly full.

The invention, while not limited thereto, is especially useful in connection with storage tanks of liquid fuel. As a single illustrative example, the mean of this invention is adapted for use 10 in connection with storage tanks for fuel oil. Particularly, when such tanks are located inside a building and are filled by an operator from outside the building, the invention affords a convenient means for warning the operator when the tank is nearly full so that he may discontinue 15 the filling operation in time to prevent overflowing the tank.

The invention has for an object the provision of a signaling means operable by air derived from 20 the vent passage of the tank and a means in said passage normally diverting enough air therefrom to said signal to operate the same, said means being movable by a float located in the upper part of said tank when the liquid rises 25 to a predetermined level in said tank, to a position to open said passage for the usual venting flow of air therethrough—diverting the flow of air from the signaling means to stop the operation of the same.

30 The invention also has for an object to provide a whistle as a simple and inexpensive form of air-operated signal.

Another object of the invention is to mount the whistle in said vent passage so that the 35 whistle itself blocks substantially all the air flow through said passage, except through the whistle openings, and to bodily move the whistle by the float as and under the condition above described to fully open said passage and discontinue operation of the whistle.

Another object of the invention is to provide 40 a whistle or other air-operated signal which may be remotely located from the tank and connected by a conduit to said vent passage, and to provide 45 a valve in said passage above the point of entry of said conduit—said valve being operable by the float as and under the condition above described, to open said passage but being normally positioned to close the same and divert the 50 air flow to said conduit and whistle.

A further object of the invention is to provide 55 a whistle of improved construction with a carrier therefor capable of connection to said float or to said conduit.

55 These objects will best be understood as the

detailed description proceeds and they will be particularly pointed out in the appended claims.

The invention will be disclosed with reference to the accompanying drawing, in which:

Fig. 1 is a fragmentary sectional view of a 5 storage tank having a signaling means embodying the invention;

Fig. 2 is a similar view showing a modification;

Figs. 3 and 4 are sectional plan views taken on the lines 3—3 and 4—4, respectively, of Fig. 10 1; and

Fig. 5 is an enlarged sectional view showing the detail of the mounting of the whistle.

Referring to the drawing, a storage tank is indicated in part at 10 and 11 is the usual interiorly-threaded opening to receive a vent pipe, by means of which air may pass into and out of the tank as liquid discharges from or enters, respectively, the tank through the usual inlet and outlet, not herein shown. 20

The signaling device of this invention is applied to a special fitting 12, having a passage 13 therethrough. Fitting 12 has an exteriorly threaded lower end to screw into tank opening 11 and an interiorly threaded upper end into 25 which the vent pipe 14 is threaded. Intermediate its ends, the passage 13 is provided with a shoulder 15 forming a seat for a carrier 16 of annular form. This carrier has a plurality (three as shown) of depending arms 17, the lower ends 30 of which are turned inwardly and joined to a central hub 18. A small rod 19 is threaded into hub 18 and depends therefrom into the upper portion of tank 10. Rod 19 carries a float 20, held thereto by upper and lower washers 21 35 which frictionally grip the rod and firmly hold the float in place but allow adjustment of the float vertically on the rod, whenever necessary or desired. The outside diameter of float 20 is less than that of opening 11 so that the float 40 can be inserted into the tank through such opening.

The carrier 16 in that form of the invention shown in Fig. 1 carries a whistle. A desirable construction of the whistle is shown in Fig. 5. 45 The whistle is composed of two parts 22 and 23 of thin sheet metal, each having a hole 24 of small diameter therethrough. The lower part 22 is generally cup-shaped in form with an outward flange 25 bordering its upper end. The 50 cup-shaped part fits within the opening in the carrier and its flange rests on a seat 26 provided near the upper end of the carrier. Embracing this seat, and slightly inturned to partially overlie it, is a circular lip or bead 27. The 55

upper whistle part 23, in the shape of a circular disc, bowed upwardly as shown, is sprung into place with its lower margin pressing on the flange 25 to hold the part 22 in place and its upper 5 margin held beneath bead 27. The whistle construction disclosed is desirable, important and preferred but other constructions may be used and the invention, in its broader aspects, is not limited to the one construction herein disclosed.

10 Above the whistle, some suitable stop is provided to limit its upward movement under the action of float 20. Conveniently, a pin 28 is passed into passage 13 through a hole 29 in its wall, to extend diametrically across said passage

15 with its inner end seated in a blind hole 30 in said wall. The outer end of hole 29 is then closed to hold pin 28 in place by a screw 31, threaded into said end of the hole.

This pin also retains the whistle in place after 20 it has been assembled in fitting 12 by dropping it, together with its carrier and rod 19, into the upper end of passage 13. The float 20 is then slipped on rod 19 to complete the assembly.

The lower part of passage 13 (below the 25 whistle) preferably has a lateral outlet 32. When the invention is used as shown in Fig. 1, this outlet has no function and it is closed, as by the plug 33.

In that form of the invention shown in Fig. 2, 30 the outlet 32 is utilized, the plug being removed and replaced by a pipe 34 of suitable length and shape to extend to the desired location. On the end of pipe 34 is a head or carrier 35, in which a whistle of the same form as above described is 35 mounted in the same way. Carrier 35 has a central hole 36 therein affording communication between pipe 34 and the whistle. The carrier 16 with its attached guide arms 17 and rod 19 with float 20 are provided as in the first form, 40 except that the carrier has mounted in it an imperforate circular disc 37.

In operation, the carrier 16 normally rests on its seat on shoulder 15, whereby only a vent 45 opening of restricted area is then available, viz., the whistle openings 24. The float 20 lies in the upper part of the tank 10 and the liquid does not reach and move the float until the tank is nearly full, although the level at which the float 50 will act is susceptible of variation by the adjustment described, throughout a substantial range. As soon as filling of tank 10 commences, the inward rush of liquid forces air to pass out of the tank at relatively high velocity through the whistle and thus a signal is given to the operator. In the case of Fig. 1, the whistle signal is 55 transmitted through the vent pipe 14 to the outer end thereof. When this arrangement is not desired, that shown in Fig. 2 is used, which enables the signal to be located remotely or

in any place desired independently of the location of the vent pipe. In the case of an inside tank, the Fig. 2 arrangement enables the alarm to be given inside the building in which the tank is located, while the Fig. 1 arrangement 5 enables the alarm to be given outside to the operator who is filling the tank. The whistling continues until the liquid reaches a predetermined level in the tank, when it is stopped because the float 20 has raised the carrier 16 from 10 its seat 15. In each form of the invention, the raising of the carrier opens an unrestricted vent—the passage 13—and diverts most of the air from the whistle. In any case, there is no longer any air passing through the whistle at 15 sufficiently high velocity to operate it. As soon as the whistling ceases, the operator knows that the tank has been sufficiently filled and he stops the filling operation.

What I claim is:

1. The combination with a tank for liquid having a vent passage with a valve seat formed therein, of an air-operated signal connected to said passage at a point below said seat, a valve member normally positioned on said seat to close 25 said passage and divert air to said signal, and a float in the upper part of said tank connected to unseat said valve and open said passage when the liquid in said tank rises to a predetermined level.

2. The combination with a tank for liquid, having a vent passage and a seat intermediate the ends of said passage, of a valve normally positioned on said seat to block off air flow through said passage, a whistle remote from said 35 passage, a conduit connecting the whistle to said passage at a point below said valve, and a float in the upper part of said tank connected to said valve and operable when the liquid in said tank rises to a predetermined level to unseat said 40 valve and open said passage to divert air flow from said conduit.

3. In apparatus of the class described, a carrier having a cylindrical recess in one face thereof and having a smaller passage extending 45 from the bottom of said recess to the opposite face thereof, said carrier having an annular ledge embordering the upper edge of said recess and an annular bead embordering said ledge and extending upwardly from and then inwardly 50 over said ledge, a whistle section having an out-turned flange, said section mounted in said recess with its flange seated on said ledge and within said bead, and a second whistle section of outwardly 55 bowed form having a central perforation and having its marginal part resting on said flange and held between the latter and said bead.

HARRY F. TAPP.
